UNITED STATES PATENT OFFICE.

JAMES H. SAGER, OF ROCHESTER, NEW YORK.

DESIGN FOR A BICYCLE-SADDLE.

SPECIFICATION forming part of Design No. 28,296, dated February 15, 1898.

Application filed October 14, 1897. Serial No. 655,220. Term of patent 7 years.

to all whom it may concern:

Be it known that I, JAMES H. SAGER, a citizen of the United States, and a resident of the city of Rochester, in the county of Monroe and State of New York, have invented and produced a certain new and original Design for Bicycle-Saddles, of which the following is specification, reference being had to the accompanying drawings, in which—

Figure 1 shows a top view of a bicycle-saddle embodying my design. Fig. 2 is a side elevation, and Fig. 3 is a rear elevation. Fig. 4 is a cross-section of the saddle through the center of the depressions A² A³.

The leading features of my design consist of the contour and proportion of the saddle herein set forth.

The design consists of two similarly-proportioned cylindrical parts A A' and between and connected with them the depressed elongated portion B, which is upon the same base as the parts A A', and one end of which forms, with the surfaces of the parts A A', the concave curvature b at the cantle of the saddle. Merging into the portions A A' are two wedge-

shaped portions C C', (see Fig. 2,) whose inner sides are continuous with the flat surface of the portion B, but substantially at right angles thereto, and whose outer faces are continuous with the outer cylindrical surfaces 30 of the portions A A' in the concave curvatures D D'. The pommel end of the portion B is connected as shown at B', extends somewhat beyond said wedge-shaped portions C C', and in connection with said portions C C' forms 35 the pommel of the saddle. The top surface of each portion A A' has at its center a depression A² A³, (see Figs. 1 and 4,) and said top surfaces are respectively united to the cylindrical surfaces a a' by curved edges E E'. 40

Having described my invention, what I claim as new, and desire to secure by Letters Patent, is—

The design for a bicycle-saddle substantially as shown and described.

JAMES H. SAGER.
